UNITED STATES PATENT OFFICE.

ELVIN H. JOHNSON, OF CHICAGO, ILLINOIS.

DESIGN FOR A TIRE TREAD.

Application filed December 7, 1922. Serial No. 4,517. Term of patent 7 years.

To all whom it may concern:

Be it known that I, ELVIN H. JOHNSON, a citizen of the United States, and a resident of the city of Chicago, county of Cook, and State of Illinois, have invented a new, original, and ornamental Design for a Tire Tread, of which the following is a specification, reference being had to the accompanying drawing, forming a part thereof, and in which—

Fig. 1, is a fragmentary plan view of a tire tread embodying my new design, and

Fig. 2, is a fragmentary sectional view of the same.

I claim:

The ornamental design for a tire tread, as shown.

Signed at Chicago, in the county of Cook and State of Illinois, this 17th day of November, 1922.

ELVIN H. JOHNSON.
